United States Patent Office

Des. 203,862
Patented Feb. 22, 1966

203,862

DESK LAMP

Michael S. Lax, New York, N.Y., assignor to Lightolier
Incorporated, New York, N.Y., a corporation of New York

Filed Mar. 18, 1965, Ser. No. 84,345

Term of patent 14 years

(Cl. D48—20)

FIG. 1

FIG. 3

FIG. 1 is a side elevational view of the desk lamp showing my new design in collapsed condition;

FIG. 2 is a rear elevational view thereof;

FIG. 3 is a bottom plan view thereof;

FIG. 4 is a side elevational view showing the desk lamp in operative position with the reflector inclined and

FIG. 5 is a top plan view of the desk lamp in operative condition with the reflector in another position.

I claim:

The ornamental design for a desk lamp, substantially as shown and described.
